UNITED STATES PATENT OFFICE.

ALBERT MATHA, OF CHICAGO, ILLINOIS.

BASEBALL GAME APPARATUS.

Application filed January 26, 1924. Serial No. 688,636.

To all whom it may concern:

Be it known that I, ALBERT MATHA, a citizen of the United States, and a resident of Chicago, in the county of Cook and State 5 of Illinois, have invented certain new and useful Improvements in Baseball Game Apparatus, of which the following is a description, reference being had to the accompanying drawings, which form a part of my 10 specification.

My invention relates to a game apparatus adapted for indoor use in playing the game of base ball and consists in providing a suitable playing field or board provided with 15 manikins in representation of and positioned to indicate the different players and fielders as employed in the game of base ball; the fielders being preferably stationarily secured in place in any suitable manner on the playing 20 board; while the pitcher and the batter manikins are movably mounted in their respective positions, so that the pitcher may project or throw a suitable ball and the batter actuated to strike at the ball; the pitcher 25 manikin and batter manikin being actuated by separate mechanisms intended to be manually operated by different individuals playing the game.

My invention and its advantages will be 30 readily comprehended from the detailed description of the accompanying drawings, wherein:—

Figure 1 is a perspective view of my improved game apparatus, with a portion 35 shown in section.

Figure 2 is an enlarged sectional view taken on the line 2—2 of Figure 1 with intermediate portions broken away, illustrating the pitcher operating mechanism.

Figure 3 is a detail perspective view of the stop or holding element of the pitcher operating mechanism.

Fig. 4 is a bottom plan view of a portion of the playing board illustrating the pitcher and batter operating mechanisms.

Figure 5 is a detail view partially in section of the batter manikin mounting and a portion of the operating mechanism therefor.

Figure 6 is a detail view, partially in section, of the outer end of the batter manikin operating mechanism.

Figure 7 is a detail view in perspective of the method of mounting the batter manikin.

My invention relates to a game apparatus for the indoor playing of the game of base

ball and consists of a suitable playing board 10, representing the playing field, preferably provided with the depending sides or marginal portions 11 in order to support the 60 playing field or board 10 a slight distance above the bottom 12 of a suitable enclosing element or container which latter is provided with the upstanding sides 13 to constitute the walls of the playing field and 65 provide a suitable enclosure therefor to maintain the ball on the "playing field."

The playing board or field 10 is provided with the outline of a diamond comprising the base lines and bases; with the 70 fielder manikins, shown at 14, suitably positioned on the playing board and secured thereto in any desired manner so as to remain in upright position. The playing field or board 10, at points adjacent to first base 75 and third base and adjacent to the side walls 13, is provided with vertically disposed strips 15 preferably equal to the distance between the side walls 13 and the bases, for the purpose of indicating "foul" territory, namely the "foul" lines of the playing field, so that when the batted ball strikes either one of the strips 15, the batted ball will constitute a "foul" ball.

The pitcher manikin 16, which may be of 85 metal, wood or any other suitable material having sufficient rigidity, is pivotally mounted, at a point adjacent to the foot of the manikin disposed toward the playing field as at 17, to an upstanding lug of a plate 90 18 which is secured on the playing field or board against movement. The playing field or board 10, adjacent to the plate, is provided with a slot 19 through which a projection 20 of the pitcher manikin 16 extends; 95 the projection 20 being preferably arranged at a rearward inclination as shown in Figure 2. The projection 20 has one end of a suitable coil spring 21 secured thereto, with the other end of the spring secured to a holding element 22 which may be either in the nature of suitably looped wire or a metallic plate having a longitudinal slot, with a setscrew or bolt 23 disposed through the playing board 10 and either between the parallelly disposed portions of the bent wire, or through the slot of the plate as the case may be, and held in place by a washer and nut as at 24. With this construction it is apparent that the spring tension may be regulated 100 by sliding the holding element 22 either toward the extension 20 of the pitcher manikin

or farther therefrom and then screwing the washer and nut 24 onto the bolt 23 so as to clamp the holding element in place. By adjusting the tension of the spring 21, the speed or action of the pitcher manikin may be varied and controlled. The extension 20 of the manikin is also provided with a rod 25 extending in a direction opposite to that of spring 21 and toward one end of the playing board, where the wire is looped or provided with a finger grasp as shown in Figure 1, at which point the end wall 13 and portion of the bottom 12 of the enclosing element is cut away as shown at 26 in order to permit access to the operating rod 25. The operating rod 25 is preferably provided with a bend or shoulder as at 27 in Figure 2 in order that the pitcher manikin may be held in its tilted or pitching position by means of the holding element 28 which is shown in the nature of a wire bent in the form of a link with the inner end thereof bent downwardly as shown at 29 in Figures 2 and 3 so as to engage with the shoulder or bend 27 of the operating rod 25 when the latter has been pulled outwardly toward the end of the apparatus and moved downwardly as indicated in dotted lines in Figure 2. This will hold the pitcher manikin in pitching position until it is desired to pitch the ball. The holding element 28 is secured to the under side of the playing board 10 in any suitable manner as for example by a bolt, washer and nut; the bolt passing between the looped end of the element 28, as shown at 30 in Figure 2.

It is apparent from the construction shown that when rod 25 is pulled outwardly or toward the end of the playing board, the pitcher manikin will tilt toward the out-field about pivotal point 17 and into position for throwing the ball when the operating rod 25 is released; the pitcher manikin being returned to normal position through the tension of spring 21.

The playing board 10, at a point in alignment with the forward foot of the pitcher manikin, is provided with an adjustable stop in the nature of a set-screw 31 with which the free or forward foot of the pitcher manikin contacts when rod 25 is released and the spring 21 comes into play. By screwing the set-screw 31 upwardly, it is apparent that the pitcher manikin will be brought to rest in advance of the moment induced by the set-screw 31, when the latter is screwed down in the position shown in Figure 2. With the set-screw 31 screwed upwardly as stated, the pitcher manikin will be brought to rest before it reaches a position perpendicular to the playing field as shown in Figures 1 and 2, namely with the pitcher manikin slightly tilted rearwardly. Such positioning of the pitcher manikin will cause the ball to be projected or thrown with a "drop"

namely at a slightly higher elevation than would be the case where the manikin is brought to rest so as to be positioned as shown in Figure 2.

The playing board 10, adjacent to the home-plate position, is provided with an opening 32 and with a plate 35 which is shown in the nature of a strip of metal, one end whereof is apertured to receive a suitable bolt 36 whereby the plate is held flush with the top of the playing board; while the other end is bent downwardly through the opening 32 in the playing board and rearwardly so as to provide a portion 37 disposed substantially parallel with the upper portion 38 of the strip; the two portions 37 and 38 providing a suitable pivotal mounting for the batter manikin 39, the bottom whereof is provided with an extension 40 adapted to pass through the enlarged aperture 41 of the upper portion 38 and be disposed intermediate of the parallelly disposed portions 37 and 38 thereof. The lower end of the extension 40 is shown reduced as at 40^a and is disposed through a smaller aperture 42 in the parallel portion 37 of the strip or plate 35. With this construction, the batter manikin is pivotally held in proper position on the playing board and the reduced portion 40^a, which may be angular in cross section, is adapted to receive a link or arm 43, see Figures 4 and 5, whose outer end is provided with a rod 44 which extends toward one side of the playing board and adjacent to a suitable opening 45 formed in the depending side portion of one of the side walls 13 of the enclosing element, as shown in Figure 1, where the rod 44 is shown bent into loop form at 46 to provide a suitable finger grasp. The bottom of the playing board 10, adjacent to the opening 45 in the side wall 13, is provided with a stop member 47 shown in the nature of a wire, bent into loop form as shown in Figure 6, with one portion extending flush with the bottom of the playing board 10 and secured thereto by screw-bolt and nut as at 48 in Figure 6; while the forward end of the looped wire is bent downwardly at right angles to receive the pull-rod or wire 44; the finger-grasp portion 46 whereof engages the bent portion of stop member 47 and prevents the too far movement of the rod or wire 44 in one direction. The arm 43 has one end of a suitable spring 49 secured thereto, (see Figure 4); while the other end of the spring 49 is secured to the bottom of the playing board 10 so as to cause the arm 43 and therefore the batter manikin to return to normal position.

With the construction shown, it is apparent that when rod or wire 44 is pulled outwardly through opening 45 in Figure 1, the batter manikin 39 will be oscillated

about the extension or axis 40 so as to swing its bat rearwardly and upon releasing the rod 44, spring 49 will cause the arm 43 and the batter manikin to oscillate back to normal position, namely so as to swing the bat forward.

The playing board 10, at a point rearward of the batter manikin and "home plate" is shown provided with a "back-stop" of cardboard or other suitable material and consisting of a vertically disposed portion 50 suitably secured to the playing-board at a slight distance removed from the enclosure wall 13 and of proper height and terminating in the forwardly disposed overhanging portion or canopy 51. The portion 50, at a point in alignment with the "home-plate" is provided with an opening 52. This provides a combined "back-stop" and "umpire" so far as "strikes" are concerned. If the ball has been properly thrown across "home-plate" and goes through opening 52, it will constitute a "strike"; on the other hand if the ball strikes the "back-stop" and the batter manikin has not been operated, it would constitute a "ball"; the construction preventing any chance for argument between the parties playing the game.

The apparatus and player manikins may be made of any suitable light material, either card-board or sheet metal, and a small ball of proper weight may be employed; the ball being inserted in a pocket 53 formed in the upraised arm of the pitcher manikin 16. The ball having been inserted in the pocket 53, pull-rod or wire 25 is pulled outwardly through opening 26, causing the pitcher manikin 16 to be tilted backwardly. Upon releasing the pull-rod 25, spring 21 will cause the manikin 16 to swing forwardly and the sudden engagement of the forward foot with the stop screw 31, will cause the ball to be thrown toward the batter; the speed and down "curve" of the ball being determined by adjustment of spring 21 and stop-screw 31.

I have described my invention in terms employed merely as terms of description and not as terms of limitation, as structural modifications are possible and may be made without, however, departing from the spirit of my invention.

What I claim is:—

1. A game apparatus of the character described, comprising a playing board provided with the outline of a base-ball diamond, with openings through said board adjacent to the "pitcher's box" and "home-plate", a bracket secured on the board adjacent the opening at the "pitcher's box", a "pitcher" manikin fulcrumed at one foot on said bracket to tilt rearwardly, the "pitcher" manikin being provided with a ball-holding pocket, the base of the "pitcher" manikin being provided with an extension disposed

through the adjacent opening in the playing-board, tension-applying means secured to said extension and to the bottom of the playing board, adapted to return the "pitcher" manikin to normal upright position, adjustable means whereby the degree of return movement and the normal position by the "pitcher" manikin may be determined, means, operable from the edge of the playing-board, whereby the "pitcher" manikin may be actuated, a "batter" manikin provided on the bottom with an extension disposed through the opening adjacent to "home-plate" and rotatably mounted beneath the playing-board, a link secured to said extension beneath the board, tension-applying means secured to said link for returning the "batter" manikin to normal position, and means, operable from an edge of the playing-board whereby the "batter" manikin may be rotated against the action of the tension-applying means.

2. In a game apparatus of the character described, a playing-board provided with the outline of a base-ball diamond and an opening, a "pitcher" manikin provided with a ball-holding pocket while the base is provided with a depending extension disposed through the opening in the playing-board, means whereby the "pitcher" manikin is tiltably mounted to swing rearwardly, adjustable tension means connected with said extension whereby the "pitcher" manikin is returned to normal position, means secured to said extension beneath the playing-board whereby the "pitcher" manikin may be operated from one side of the playing-board, and adjustable means intermediate of the playing board and the manikin whereby the "pitching" moment of the "pitcher" manikin may be regulated.

3. In a game of the character described, a playing-board provided with an opening, a "pitcher" manikin with a ball-holding pocket and a depending extension, adjacent to one end of the base of the manikin, disposed through said opening, the manikin being pivoted on the board so as to tilt rearwardly, a spring secured at one end to said extension, adjustable means, secured to the lower side of the playing-board and to the other end of the spring, whereby the tension of the spring may be controlled, an operating rod secured to said extension and extending to one side of the board, means whereby said rod may be held in pitcher setting position, and adjustable means whereby the pitching moment and normal position of the "pitcher" manikin may be controlled.

4. In a game apparatus of the character described, a playing-board provided with base ball player manikins, the "pitcher" manikin being mounted to tilt rearwardly into pitching position, while the "batter" manikin

manikin is rotatably mounted, a marginal enclosure disposed about the playing-board and extending beneath the same, two of the depending sides of the marginal enclosure 5 at points beneath the bottom of the playing-board being provided with openings, an operating rod adapted to tilt the "pitcher" manikin, with the outer end of said rod disposed at one of said openings in the marginal enclosure, means whereby said rod 10 may be held in pitcher tilting position, and an operating rod adapted to rotate the "batter" manikin, the outer end of said second rod being disposed at the other opening in 15 the marginal enclosure.

5. In a game apparatus of the character described, a playing-board provided with the outline of a base-ball diamond and player manikins disposed in their respective positions, a marginal enclosure for said playing board arranged to extend beneath the plane of said board, means whereby the "pitcher" manikin is pivotally mounted to tilt rearwardly, an operating rod disposed beneath the playing board and operatively connected at the inner end to the "pitcher" manikin whereby the latter may be tilted into pitching position, adjustable tension-applying means for returning the "pitcher" 25 manikin to normal position, an opening in the marginal enclosure for the outer end of said operating rod, means whereby the "batter" manikin is rotatably mounted, an operating rod for actuating said "batter" 30 manikin, an opening in the marginal enclosure for the outer end of said rod, means for returning the "batter" manikin to normal position, and an "umpire" element arranged on the playing-board rearward of the "batter" manikin in slight spaced relation with the enclosure, whereby the character of the pitched ball may be determined. 35

6. In a game apparatus of the character described, a playing-board provided with the outline of a base-ball diamond and with player manikins arranged in their respective playing positions, a marginal enclosure for the playing-board extending beneath the bottom, the "pitcher" manikin being tiltably mounted, means for tilting the "pitcher" 40 and to quickly return the same to normal position, the "batter" manikin being rotatably mounted, means whereby the "batter" manikin may be rotated and automatically 45 returned to normal position, a "back-stop" element secured to the playing-board rearward of the "batter" manikin and in spaced relation with the marginal enclosure and provided with an opening at a predetermined 50 point whereby to determine the character of the ball pitched, and vertically disposed elements arranged on the playing-board intermediate of first and third base and the adjacent portions of the marginal enclosure. 55

65 7. In a game apparatus of the character

described, a playing-board provided with a depending marginal portions and having the outline of a base-ball diamond thereon, a marginal enclosure for said board depending beneath the bottom thereof, player manikins secured on the playing-board, the "pitcher" manikin being provided with an extension disposed in an opening in the playing-board, with one arm of the manikin provided with a ball-receiving pocket, means whereby the "pitcher" manikin is secured on said board so as to tilt rearwardly, adjustable tension means secured to said extension whereby the "pitcher" manikin is returned to normal position, an operating rod secured to said extension and extending toward one side of the playing-board and the marginal enclosure, means whereby the "batter" manikin is rotatably mounted on the board, said means extending through an opening in the playing-board to the under side thereof, an operating rod whereby said manikin may be rotated, the outer end of said rod being disposed adjacent one side of the playing-board and marginal enclosure, a vertically disposed element secured on the playing-board rearward of the "batter" manikin in spaced relation with the marginal enclosure whereby the character of the pitched ball may be determined, and means intermediate of the 95 marginal enclosure and first and third base whereby the character of a batted ball may be determined. 99

8. In a game apparatus of the character described, a "batter" manikin, the base whereof is provided with a depending extension, an angular plate secured to the playing-board and apertured to receive said extension and to rotatably hold the "batter" manikin in place, a spring-controlled link secured to said extension, an operating rod secured to said link, and means whereby the free end of said rod is held in position and the normal position of the "batter" manikin determined. 100

9. In a game apparatus of the character described, a playing-board provided with the outline of a base-ball diamond and with an opening therethrough, a "pitcher" manikin pivotally mounted adjacent to said opening to tilt rearwardly and having a ball-receiving pocket, the bottom of the manikin being provided with an extension disposed through said opening, tension-applying means arranged on the bottom of the playing-board and secured to said extension of the "pitcher" manikin whereby the pitcher is returned to normal position, means operable from the end of the playing-board for actuating the "pitcher" manikin, and adjustable means whereby the pitching moment of the "pitcher" manikin may be controlled. 115
